SAFETY RAZOR

Filed April 24, 1931

INVENTOR
Nicholas Testi
BY
P. F. Brown,
ATTORNEY

UNITED STATES PATENT OFFICE

NICHOLAS TESTI, OF NEW YORK, N. Y., ASSIGNOR TO GILLETTE SAFETY RAZOR COMPANY, OF BOSTON, MASSACHUSETTS, A CORPORATION OF DELAWARE

SAFETY RAZOR

Application filed April 24, 1931. Serial No. 538,570.

My invention relates to improvements in the class of safety razors in which a blade is retained in shaving position between clamping members, such as a guard member and a cap or backing member.

An object of my invention is to provide improved means for retaining the blade between clamping members including means for readily connecting the cap or backing member with the guard member and releasing said members in a simple manner.

My invention also comprises a resilient cap or backing member provided with means cooperative with the other member or its handle for retaining said members clamped against a blade and including means to operate the first named means to release the cap or backing member.

My invention also comprises novel details of improvements that will be more fully hereinafter set forth and then pointed out in the claims.

Reference is to be had to the accompanying drawings wherein:

25 Fig. 1 is a side view of my improved razor; Fig. 2 is a section on line 2, 2, in Fig. 1;

Fig. 3 is a sectional view illustrating the parts in position for clamping or releasing a blade;

30 Fig. 4 is a section on line 4, 4 in Fig. 3;

Fig. 5 is a detail section illustrating the parts in an initial position for releasing the cap member;

Fig. 6 is a broken plan view partly in section on line 6, 6 in Fig. 2;

Fig. 7 is a side view illustrating a modification;

Fig. 8 is a section on line 8, 8 in Fig. 7; and

40 Fig. 9 is a view similar to Fig. 8, showing the parts in cap releasing position.

Similar numerals indicate corresponding parts in the several views.

Blade clamping members are indicated at 1 and 2 adapted to clamp a blade 3 therebetween for shaving. The member 1 is shown as a guard member and the member 2 is shown as a cap or backing member for the blade. Any suitable means may be provided for positioning the blade between the members for shaving. As illustrated, the cap

member 2 is provided with a split projection or stem 4 adapted to pass through apertures 5 in the blade and through openings 6 in the guard member for positioning the blade between said members in a well known way. 55 The guard member 1 is shown provided with a tubular handle 7 which may be attached to the guard member in any desired way.

The cap or backing member 2 is shown provided with a substantially centrally disposed 60

projection 8 that is adapted to pass through an aperture 9 in the blade and through an opening 10 in the guard member and into the bore 11 of the handle. The free end of

projection 8 is resilient to engage the handle 65

to retain the cap in clamping position against the blade. I have illustrated the pro- 70

jection 8 as provided with a stop shoulder 12 to engage an abutment 13 on the handle, within its bore, for retaining the cap in shav- 75

ing relation against the blade, as in Figs. 2 and 8. By preference the projection 8 is

made bifurcated, as by splitting said pro- 80

jection from its outer end inwardly at 14, each prong of the projection being shown 85

provided with a stop shoulder 12 to engage a corresponding abutment 13 in the handle. The arms or prongs of the projection 8 are

set in a spread position to move outwardly to cause the stops 12 to engage the abutments 90

13, and may be moved inwardly to release said stops from said abutments, (Figs. 5 and 9). The cap 2 is preferably made resilient, as by being made of a piece of spring metal, and the projection 8 may be riveted thereto, 95

whereby when the cap is placed against a blade with the projection 8 passing into the handle 7, as in Fig. 3, the outer inclined sur- 100

faces 15 of the projection 8 are slid along the inwardly inclined surfaces 16 of the handle 90

to cause the prongs or arms of the projection 8 to move inwardly, as in Fig. 3, to permit the

stops 12 to pass beyond and engage the abut- 95

ments 13 to retain the cap in clamping rela- 100

tion upon the blade, as illustrated in Figs. 2 and 8.

Since the split portions of the projection 8 are adapted to spring outwardly to engage these stops 12 with the abutment 13 of the handle I provide means to move said projec- 100

tion reversely to release the stop 12 from the abutment 13 to permit removal of the cap 2 from the holder. In the example illustrated in Figs. 1 to 6 I provide a rod or bar 17 slideable in the bore of handle 7 and adapted to engage the inner end of projection 8 to move its stop 12 away from the abutment, when said rod or bar is moved inwardly. The rod or bar 17 is shown tubular, for the sake of lightness in weight, and its bore 18 is adapted to receive the adjacent end of projection 8. The inner edges 19 of bore 18 are shown inclined to engage and slide freely along the inclined or tapered surfaces 15 of the projection 8. Longitudinal movement of the rod or bar 17 along the handle 7 is controlled by a pin 21 carried by the handle and operative in a slot 22 in the handle.

When a blade is to be inserted between the guard and the cap the latter will be removed from the guard, the blade will be placed upon the latter and the cap will be applied on the blade, whereupon the projections 4 and 8 will pass through the apertured portion of the blade. When the cap engages the blade the cap will be pushed against the blade and will be bent sufficiently to enable the stops or shoulders 12 to spread and engage under the abutments 13, Fig. 2. The tension of the cap 20 will be in a direction away from the blade, hence will tend to draw and retain the stops 12 against the abutments 13, whereby the cap will be retained pressing on the blade and the latter will be clamped between the guard and the cap in shaving position. When it is desired to release the cap, for removal of the blade, the rod or bar 17 will be pushed inwardly along the handle until the inner end of the bar engages the adjacent end of projection 8, and continued sliding of the bar will bend the end of projection 8 toward the longitudinal axis of the handle to release the stops 12 from the abutments 13, as in Fig. 5, whereupon the cap may be withdrawn and removal 45 of the blade may be effected.

In Figs. 7, 8 and 9 the handle is shown provided with finger pieces 23 adapted to be pressed inwardly, into the bore of the handle, to engage the adjacent ends of the projection 8 to release its stops 12 from the abutments 13. The finger pieces 23 may be formed by appropriately slitting the handle at 24, leaving base portions of the finger pieces attached to the handle. The handle may comprise resilient metal to enable the finger pieces to spring outwardly and so remain in normal position, whereby when the cap is applied on the blade the finger pieces will not interfere with stops 12 engaging the abutments 13, as in Fig. 8.

By means of my improvements the cap or backing member 2 may be readily applied over a blade on the guard member and be retained in clamping position thereon by merely applying the cap over the blade on the

guard and pushing on the cap to cause its projection 8 to engage the abutments 13 connected with the guard, the resiliency of the cap freely permitting such operations of the parts. When the stops 12 are moved away from the abutments 13 the outward spring tendency of the cap will serve to withdraw the stops from the abutments, as in the position of Fig. 3, to permit removal of the cap from over the blade.

Changes may be made in the details set forth, without departing from the spirit of my invention, within the scope of the appended claims.

Having now described my invention what I claim is:

1. A safety razor comprising a guard provided with a handle, said handle having a bore and abutments within the bore, a cap having a bifurcated projection providing separate arms, each arm having a stop to engage an adjacent abutment, said projection being adapted to enter said bore to engage the stops with the abutments, and means simultaneously to release the stops from the abutments.

2. A safety razor as set forth in claim 1 in which the arms of the projection have inclined portions and the bore of the handle has inclined surfaces to be engaged by said inclined portions to permit passage of the stops through the bore to engage said abutments.

3. A safety razor as set forth in claim 1 in which the cap is resilient to enable the stops to engage the abutments.

4. A safety razor comprising a guard provided with an abutment, a handle having a bore, a cap having a projection provided with a stop to engage said abutment, and a rod slideable along said handle and adapted to engage said projection to release the stop from the abutment.

5. A safety razor as set forth in claim 4 in which the projection has an inclined inner portion to be engaged by said rod to move the stop away from the abutment.

6. A safety razor as set forth in claim 4 in which the cap is resilient to retain the stop and abutment in engagement and to withdraw the stop from the abutment when the latter are released.

7. A safety razor comprising a guard provided with a handle, said handle having a bore provided with an abutment, and a cap having a projection provided with a stop to engage said abutment, the handle having a movable finger piece to engage the projection and move it to release its stop from the abutment.

8. A safety razor as set forth in claim 7 in which the cap is resilient to retain the stop and the abutment in engagement.

9. A safety razor comprising a guard provided with a tubular handle, a cap having a compressible stem arranged to extend

through the guard and engage the interior of said handle to hold the cap in place, and a releasing member slidable within the handle to and from position to engage and compress said stem.

- 6 10. A safety razor comprising cap and guard members, one having a tubular handle and the other a split stem with locking shoulders therein arranged to engage the interior of the tubular handle, and an unlocking device slidable within the handle to and from position to engage the stem and hold the locking shoulders in releasing position, the stem being thereupon movable away from
10 15 the unlocking device.
